UNITED STATES PATENT OFFICE.

EDWARD H. McCLOUD, OF COLUMBUS, OHIO, ASSIGNOR TO THE KINNEAR MANUFACTURING COMPANY, OF COLUMBUS, OHIO, A CORPORATION OF OHIO.

DOOR AND THE LIKE.

1,342,751.

Specification of Letters Patent.

Patented June 8, 1920.

Application filed October 4, 1918. Serial No. 256,924.

To all whom it may concern:

Be it known that I, EDWARD H. McCLOUD, a citizen of the United States, residing at Columbus, in the county of Franklin and State of Ohio, have invented a certain new and useful Improvement in Doors and the like, of which the following is a specification.

This invention relates to a door of the variety that is lifted and then deflected at its upper end outward from the door opening onto a horizontal track or support for the end. When such a door is heavy it is common to attach an operating cord or chain, provided with a counter-weight, to the lower end of the door so as to facilitate its operation. But when the upper end of such a door is deflected onto the support approximately one half the load of the door is transferred to the support and the lifting force thereby relieved by that much. Hence in counter-weighting such a door the counter-weighting and operating force should, in the interest of smooth and easy operation, be varied or made less when a portion of the load of the door is transferred to the support and greater when the load of the door is more largely supported by the counterbalancing means. The object of the present invention is a simplified and economical means whereby the result stated may be accomplished.

The invention is embodied in the example herein shown and described and then finally claimed.

In the accompanying drawings—

Fig. 1 is a front elevation of the door equipped with the invention.

Fig. 2 is a horizontal section on the line II—II Fig. 1 looking down.

Fig. 3 is a vertical section on the line III—III Fig. 1 looking to the right showing the door in closed position.

Fig. 4 is a similar vertical section showing the door partially raised and deflected.

Fig. 5 is a detail partly in section illustrating the means for varying the effect of the counter-weight, the position of the parts being one of those existing when the upper end of the door is supported by the track and a portion only of the weight is exerted on the door.

Fig. 6 is a detail like Fig. 5 except that the parts are shown as when the entire weight is acting on the door.

Fig. 7 is a view taken at right angles to the view shown in Fig. 5.

Fig. 8 is a detail of the equalizer for the door operating chains.

In the views 10 designates the door which may be paneled or plain as may be desired.

From the two lower corners of the door 60 project trunnions or stud shafts 11 containing rollers 12 that travel in channels 13 erected at opposite sides of the doorway.

At the two upper corners of the door are rollers 14 suitably journaled to project laterally beyond the door. Mounted near the top of the door are brackets 15 having short curved channels 16 in which the rollers 14 project and travel when the door is raised and lowered. 17 are horizontal tracks 70 placed to form continuations of the lower walls of the two curved channels 16. Connected with the stud shafts 11 of the lower rollers 12 are chains 18 and 19 passed over pulleys 20 and 21 and connected to an 75 equalizer bar 22. Connected to said equalizer is a single chain 23. The character 24 designates the counterweight the weight of which is best about equal to that of the door, said weight being provided with plain 80 links or arms 25 between which is mounted on a shaft 26 a sheave 27. Pivoted on the shaft 26 is a yoke 28 having pivoted therein a member 29 provided with a hole 29^a. The chain 23 is passed through the hole 29^a, 85 under the sheave 27 and connected to a small fixed bracket 30. The chain 23 is provided with a lug or enlargement 31 located at the point where it will engage the member 29 and support the counterweight during the 90 movement of the door from its fully closed position to the position where the load of its upper end is transferred to the track. The chain 23 is made long enough to provide for the travel of the weight through 95 said distance and then its support by the loop of said chain. When the weight is thus supported one half of its load is borne by that leg of the chain connected with the bracket 30 and the other half by the shutter. 100 In other words the lug 31 is so placed that the division of the load of the door between the chain 23 and the tracks is accompanied by a substantially corresponding division of the load of the counterweight between said 105 chain and the bracket 30.

The pulleys 20 and 21 carrying the chains 18 and 19 are turned to raise or lower the door by means of an endless chain 32 engaging a wheel 33 fixed on a shaft 34, said shaft 110

34 having fixed thereon suitable gears 35
that engage gears 36 on the shaft carrying
the pulleys.

5 The forms of the parts can be changed
without departing from the gist of the in-
vention as claimed.

The invention may be useful in the con-
struction and operation of windows, parti-
tions and the like and by the term "door"

10 I include such analogous structures.

What I claim is:

1. In combination with a door, means for
deflecting the door at its upper end when
raised, means upon which a portion of the
15 weight of the door is supported when de-
flected, a counter-weight for the door, a
looped flexible member connected with the
door and with a fixed point for supporting
said counter-weight, and a lug in said flexible
20 member for sustaining said counter-weight
substantially when the door wholly supports
said counter-weight.

2. In combination with a door, means for
deflecting the door at its upper end when
25 raised, means upon which a portion of the

weight of the door is supported when de-
flected, a counter-weight for the door pro-
vided with a pivoted member, a looped flexi-
ble member connected with the door and with
a fixed point for supporting said counter-
weight, and a lug in said flexible member to
30 engage said pivoted member for sustaining
said counter-weight substantially when the
door wholly supports said counter-weight.

3. In combination with a door, means for 35
deflecting the door at its upper end when
raised, means upon which a portion of the
weight of the door is supported when de-
flected, a counter-weight for the door pro-
vided with a member pivoted to it and a sec- 40
ond perforated member pivoted in the latter,
a looped flexible member connected with the
door and with a fixed point for supporting
said counter-weight, and a lug in said flexible
45 member to engage said perforated pivoted
member for sustaining said counter-weight
substantially when the door wholly sup-
ports said counter-weight.

EDWARD H. McCLOUD.
